UNITED STATES PATENT OFFICE.

CHARLES W. LONG, OF MIAMISBURG, OHIO.

TOP.

SPECIFICATION forming part of Letters Patent No. 576,982, dated February 9, 1897.

Application filed February 12, 1896. Serial No. 579,052. (No model.)

To all whom it may concern:

Be it known that I, CHARLES W. LONG, a citizen of the United States, residing at Miamisburg, in the county of Montgomery and 5 State of Ohio, have invented certain new and useful Improvements in Tops; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

15 My invention relates to improvements in toys, with specific reference to spinning-tops.

The object of the invention is to provide a top that while spinning gives forth a shrill whistling noise as distinct from a humming 20 noise, and which is audible for a considerable distance. Among the advantages possessed by this specific form of top may be mentioned the changing of the ordinary wooden top into a top which gives forth a 25 distinct whistling noise during the entire time it is in motion.

To this end the invention consists of a construction that will be hereinafter described in connection with the accompanying drawings, 30 of which—

Figure 1 is an elevation of a top made in accordance with my invention. Fig. 2 is a section on the line $x-x$, and Fig. 3 is a section on the line $y-y$.

35 For the purposes of my invention an ordinary wooden top such as is commonly used will answer. In the portion a , which is the greatest cross-sectional diameter of the top, I bore an opening a' on a horizontal line to 40 the vertical center of the top and of a depth substantially as shown in Figs. 2 and 3.

b designates a second bore of smaller diameter which intersects the inner terminal of the first-named bore a' , and which together 45 therewith forms an elbow-chamber. The last-named bore b enters the top on the same side, and at a point slightly below the entrance of the bore a' , and extends upward on an incline until it intersects the bore a' , as 50 shown.

In order to produce a shrill whistling sound,

it is essential that the entrance to the chamber b be at a point below the widest diameter of the top, as shown in the drawings, and on an upward incline. The currents of air produced by the top while spinning are such that render the position of the chamber important. For example, there are three currents of air formed by the movement of the top—to wit, an upward and downward and a 60 central or horizontal draft. These various currents merge into one on a horizontal plane with the widest portion of the top and at some distance therefrom. If the said chamber were placed in the widest diameter of the 65 top, it will be readily seen that the suction created by the departing current of air at that point would prevent the emission of any sound; or if the said chamber were placed in the top above the widest diameter owing 70 to the rounded form of said upper portion the downward current of air would leave the top on a tangent without affecting the opening; but the chamber being below the widest diameter and entering on an upward incline 75 the upward current of air comes in direct contact with the opening. The weight of air within the chambers and the weight of the plugs c and c' are sufficient to compensate for the weight of the material removed from 80 the top in forming the chambers. Therefore the top is evenly balanced and will spin properly.

c designates a cap or plug which closes the mouth of the bore a' . The outer surface of 85 this cap lies flush with the surface of the top and conforms to the circular form thereof.

c' is a second plug or cap which closes the mouth of bore b , and which also conforms to the outer surface of the top. This cap 90 c' has a piece cut out of its edge which provides an opening or port e , communicating with the elbow-chamber. The arrangement and construction of the openings, as described above, are essential and were determined upon after long experimental effort to obtain the desired sound. 95

The top is spun in the usual manner, and during the rapid revolutions thereof the full force of air passes over the opening e and 100 causes the whistling sound mentioned.

The advantage of boring the opening b on

the incline specified is in obtaining the upward draft of the air as said air leaves the widest part of the top.

Having described my invention, I claim—

- 5 A top provided with a chamber b entering at a point below the widest diameter of said top, and inclining upwardly, and a chamber a' intersecting with the rear terminal of said chamber b , a plug c entirely inclosing said chamber a' , and a plug c' inclosing the cham-

ber b , the latter plug being provided with an opening e in the edge thereof, as herein shown and for the purposes specified.

In testimony whereof I affix my signature in presence of two witnesses.

CHARLES W. LONG.
